ART OF IMPREGNATING OR WATERPROOFING MATERIALS

Filed August 26, 1922

Inventor:

ARTHUR S. O'NEIL,

By John H. Bruminger,
His Attorney.

UNITED STATES PATENT OFFICE.

ARTHUR S. O'NEIL, OF ALTON, ILLINOIS, ASSIGNOR TO WESTERN CARTRIDGE COMPANY, OF EAST ALTON, ILLINOIS, A CORPORATION OF DELAWARE.

ART OF IMPREGNATING OR WATERPROOFING MATERIALS.

Application filed August 26, 1922. Serial No. 584,480.

This invention relates to the art of impregnating or water-proofing materials, and more particularly as applicable to paper or composition tubes for use in the manufacture of cartridges and for the purpose of water-proofing and fire-proofing the shells.

The paper used in the manufacture of paper shells for cartridges is usually of cotton or flax and the fibres are hollow so that the material is porous; the voids contain not only air but also moisture and other volatile matter which must be eliminated before the impregnation can properly enter the material.

One of the objects of this invention, therefore, is to provide a process whereby the material will be so treated as to secure uniform and complete impregnation.

Another object of this invention is to provide a process which is simple as well as effective, which is readily under the control of the operator, and whereby the impregnation will be effectively and efficiently accomplished.

Further objects will appear from the detail description taken in connection with the accompanying drawing, which shows an apparatus adapted for carrying out the process embodying this invention; it is to be understood, however, that this apparatus is only illustrative as the process may be carried out by a different apparatus and even by simple manual manipulation.

In accordance with this invention the material is first immersed in a hot bath of the impregnation and is then transferred and immersed in a bath at a lower temperature. The impregnation is preferably molten paraffin with or without a small percentage of a higher organic acid or a natural wax or gum. The first bath is maintained above the boiling point of water, preferably from 230° F. to 260° F. This causes the air enclosed within the cells of the material to expand and leave the same until the maximum expansion is reached; in addition, however, the moisture and other volatile matter within the material will be gasified and evaporated, with the result that the residual air is driven out so that the voids or cells will become filled with water vapor. The immersion in the hot bath is continued until the ebullition ceases, which can be readily observed by the operator and at

which time substantially all of the air will have been expelled, so that the voids or cells will now be completely filled with vapor.

As soon as ebullition ceases, the article is quickly transferred to the bath of lower temperature, the second bath being maintained at a temperature from 160° F. to 185° F. The immersion of the material in this second bath causes the vapor to condense in the cells or voids, forming a partial vacuum therein so that the impregnation flows into these voids or cells sealing the same. After the material has been sufficiently long in the colder bath, it is withdrawn therefrom and allowed to drain.

It is important that the material remain immersed in the hotter bath until ebullition ceases, in order that the air and other volatile matter, which does not readily condense will be driven off and replaced by vapor which will condense, since otherwise the desired reduction of pressure below atmospheric pressure in the cells or voids will not be obtained, so that the impregnation will not properly flow into and fill these voids. After this has, however, been accomplished the material should not be allowed to stand in the hot bath, for if this is permitted, the liquid pressure in the bath, which is higher than the vapor pressure in the material, will allow some of the paraffin to enter the same. This is undesirable since the flow in the colder bath will then be somewhat obstructed.

In accordance with this invention the transfer from the hotter bath to the colder bath is made quickly, so that any impregnation which may be on the surface of the material will not be allowed to harden and so that the air will not again be allowed to enter the cells before this material is immersed in the colder bath. Furthermore the material is maintained at a temperature during this transference sufficiently high to avoid any hardening or coagulation of the impregnation, and to avoid partial condensation of the vapor and entrance of air in the cells or voids. Accordingly, in order to accomplish this result the baths are not only placed closely adjacent, where transfer from one to the other can be accomplished very quickly, but both baths open to and are enclosed by the same chamber, in which the material can move from one to the other. This chamber is, therefore, heated by the

baths and maintained at the proper temperature in the chamber, in order that transfer may be effected without any appreciable reduction in temperature during such transfer. This, moreover, has the advantage, that in case any delay takes place in the transfer so that air may enter the voids, the material can be readily returned to the hotter bath and the air again expelled. Furthermore, this chamber provides an efficient place where the material may be drained after it has been immersed and withdrawn from the colder bath.

In accordance with this invention, as previously pointed out, a small percentage of a higher organic acid, such as stearic acid, oleic acid, palmitic acid, etc. or waxes, such as carnauba, Montan, bees-wax, rosin, etc. is added to the paraffin. The percentage of the addition varies from two per cent (2%) to ten per cent (10%) and it is introduced for the purpose of increasing the fluidity of the paraffin at the temperature used, thus causing freer entrance of the same into the material and also improving the water-proofing and fire-proofing properties. The addition is preferably used in the colder bath but it may be added to both baths.

Referring now to the accompanying drawing, 1 and 2 designate tanks, each of which is heated by any suitable means, such as steam coils 3, these tanks being arranged to receive the impregnation, as previously described, and providing respectively the hotter and colder baths. These tanks are placed adjacent one another and open into a casing 4 forming a chamber above and connecting the baths, and this chamber is provided with doors 5 and 6 respectively. Arranged within the chamber and above the respective baths are carriers 7 and 8 which are suspended by rods 9 and 10 and cables 11 and 12 from pulleys 13 and 14, these carriers being provided with counter-weights 15 and 16 respectively. These carriers are arranged to receive baskets 17 and 18 which carry the material which in this case consists of paper tubes 19. Suitable latching devices 20 are provided for holding the basket 18 in elevated position and between the tanks is a suitable support 21.

The operation of the apparatus will be obvious. The tank 1 is maintained at the higher temperature and the tank 2 at the lower temperature. The basket 17 is then placed on the carrier 7, the door 5 closed and the carrier lowered to immerse the basket and its contents in the tank 1. After ebullition has ceased, which can be observed through the door 5, the carrier 7 is again raised until level with the carrier 8 and the basket 17 is then moved on to the carrier 8. The carrier 8, its basket and contents are then immersed in the impregnation in the tank 2 and after a suitable period, which

can readily be determined by the operator, the carrier 8 is raised and the basket placed on the latches 20 and allowed to drain in the chamber and into the tank 2. The basket is then removed.

It is obvious that various changes may be made in details without departing from the spirit of this invention; it is, therefore, to be understood that this invention is not to be limited to the specific details shown and described.

Having thus described the invention, what is claimed is:

1. In the art of impregnating or water-proofing porous materials, the process comprising, immersing the material in a hot impregnating bath, thereafter transferring the material to and immersing the same in a bath at a lower temperature, and applying heat to the material during such transfer, substantially as and for the purpose set forth.

2. In the art of impregnating or water-proofing porous materials, the process comprising, immersing the material in a hot bath and transferring the material to and immersing the same in a bath at a lower temperature, the material being passed through a heated chamber during such transfer, substantially as and for the purpose set forth.

3. In the art of impregnating or water-proofing porous materials, the process comprising, immersing the material in a hot bath and transferring the material to and immersing the same in a bath at a lower temperature but in the same chamber, substantially as and for the purpose set forth.

4. In the art of impregnating or water-proofing porous materials, the process comprising, immersing the material in a hot bath and transferring the material to and immersing the same in a bath at a lower temperature, the material being passed during such transfer through a chamber heated by the baths, substantially as and for the purpose set forth.

5. In the art of impregnating or water-proofing porous materials, the process comprising, immersing the material in a hot bath and transferring the material to and immersing the same in a bath at a lower temperature, and allowing the material to drain while being kept heated, substantially as and for the purpose set forth.

6. In the art of impregnating or water-proofing porous materials, the process comprising, immersing the material in a hot bath and transferring the material to and immersing the same in a bath at a lower temperature, and allowing the material to drain in a chamber heated by the baths, substantially as and for the purpose set forth.

7. In the art of impregnating or water-

- proofing porous materials, the process comprising, immersing the material in a hot impregnating bath until ebullition of the volatile matter ceases, thereafter transferring the material to and immersing the same in a similar bath at a lower temperature, and applying heat to the material during such transfer, substantially as and for the purpose set forth.
- 10 8. In the art of impregnating or water-proofing porous materials, the process comprising, immersing the material in a hot impregnating bath until ebullition of the volatile matter ceases, thereafter transferring the material quickly and before the impregnation can harden on the material, to and immersing the same in a similar bath at a lower temperature, and applying heat to the material during such transfer, substantially as and for the purpose set forth.
- 15 9. In the art of impregnating or water-proofing porous materials, the process comprising, immersing the material in a hot bath, transferring the material to another bath at a lower temperature and immersing the same therein, and draining the material while being kept heated, substantially as and for the purpose set forth.
- 20 10. In the art of impregnating or water-proofing porous materials, the process comprising, immersing the material in a hot bath, transferring the material while being kept heated to another bath at a lower tem-
- perature and immersing the same therein, and draining the material while being kept heated, substantially as and for the purpose set forth.
- 25 11. In the art of impregnating or water-proofing porous materials, the process comprising, immersing the material in a hot bath and transferring the material to and immersing the same in a bath at a lower temperature, the material passing through a chamber heated by the baths, and draining the material in the chamber, substantially as and for the purpose set forth.

In testimony whereof I affix my signature this 19th day of July, 1922.

ARTHUR S. O'NEIL.
